(57) **CLAIM**

The ornamental design for an aerodynamic device for trailers and the like, as shown and described.

DESCRIPTION

FIG. 1 is a three quarter right, front, top perspective view of an aerodynamic device for trailers and the like showing our new design;

FIG. 2 is a front elevational view thereof;

FIG. 3 is an elevational view of just a left panel thereof, it being understood that the right panel is a mirror image thereof;

FIG. 4 is a top plan view thereof; and,

FIG. 5 is a bottom plan view thereof.

In the drawings, the broken lines depict a trailer and form no part of the claimed design.
